UNITED STATES PATENT OFFICE.

GEORGE L. PASS, OF QUANTICO, VIRGINIA.

INCENDIARY PROJECTILE.

Application filed September 1, 1923. Serial No. 660,594.

To all whom it may concern:

Be it known that I, GEORGE L. PASS, a citizen of the United States, residing at Quantico, in the county of Prince William and State of Virginia, have invented certain new and useful Improvements in Incendiary Projectiles; and I do hereby declare the following to be a full, clear, and exact description of the same, reference 10 being had to the accompanying drawing, forming part of this specification.

This invention relates to incendiary projectiles and has for its principal object the provision of a projectile having within it a plurality of torches which are discharged from the projectile at a given elevation or at a given time after the moment of discharge from the gun, the torches being so constructed as to embed in the woodwork 20 or textile covering of the airplane.

A further object of the present invention is the provision of a tank in the projectile containing a quantity of inflammable gas under pressure preferably liquefied, which tank is burst subsequently to the discharge of the flying torches.

Other and further objects of the present invention pertain particularly to the details of construction and will be particularly pointed out in the claims.

In the drawings,

Figure 1 is a sectional view through the projectile.

Fig. 2 is a transverse cross section.

Fig. 3 is a side elevation partly in section.

The projectile consists in a shell 10 of such size as to fit a gun of the usual type and is provided with a plurality of bores 40 such as 11 arranged in the form of a cone and also a plurality of bores such as 12 which are arranged in the form of a cylinder lying near the outer surface of the shell. These cylindrical bores are of such size as to fit the torches 15 and each communicates at the forward end of the projectile with one of the series of holes 16, best seen in Fig. 1.

A fuse 17, preferably of the time type, 50 communicates with the central passageway 20 which has a number of branches such as 21, 22, etc., leading to the rear ends of each of the bores, some of which, as previously noted, are parallel to the axis while others are at an angle thereto, the former

discharging the torches in the same direction as the travel of the shell while the bores which are at an angle cause the torches therein to depart from the path of the projectile and hence the area covered by all of the torches is materially greater than if the torches were all discharged in a substantially axial direction.

Each of the torches consists in a relatively thin cylinder 25 and is perforated as at 26 so that when the incendiary composition with which the torch is filled is set on fire by the action of the propelling charge, the flames may pass through the openings 26 so as to burn the object with which the torch may come in contact. In the center of the torch I provide a small passageway 27 in which operates a small rod 29 spring pressed outwardly in any desired manner as, for example, by the coil spring 30 which surrounds the forward end of the rod 29 between the steel spear 31 at the forward end thereof and the rounded nose 32 of the torch. At its rear end the rod 29 has a small hook 33 which normally holds the latch 34 which when freed operates under influence of the spring 36 to release the arms 37 so that the latter may spring outward and assume a position at a right angle to the axis of the rod and torch.

The operation of the device is as follows: The shell or projectile is discharged at an airplane in the usual manner, the time fuse 17 being set for the proper number of seconds so that the torches will be discharged just before the projectile reaches the airplane. When the fuse 17 functions the powder in the central passageway will be ignited burning back to the branches 21, 22, etc., which may be arranged as desired to discharge the torches simultaneously or one after the other in rapid sequence, those torches lying nearest the surface of the projectile discharging in substantially the direction of the flight of the shell while the torches in those bores angularly arranged with respect to the axis of the shell are discharged outward in conical fashion.

Should a torch strike against the wood-work of the airplane the small sharp spear head 31 will embed in the wood holding the torch so that the incendiary contents may ignite the airplane and thereby disable it. The incendiary composition may be of any desired type and should preferably be rather

slow burning in order that the torch may have a comparatively long length of life. Contact of the spear head 31 with the wood of the airplane or even with a thin light member such as the cloth covering of the wings pushes it backwardly with respect to the torch against the tension of the very light spring 30 and releases the arms 37 so that the latter open radially preventing the passage of the torch through the wings and holding the torch in such position that the flames coming through the holes 26 will ignite any combustible part of the airplane within reach of such flames. If desired there may be but a single arm, but I prefer to use three such arms spaced at an angle of 120° to each other as by using this number the arms may be materially lighter than if but a single arm is used.

20 After the torches have all been discharged the bursting charge 40 is ignited disrupting the shell and releasing its charge of inflammable gas under pressure so as to further aid in the destruction of the aircraft.

25 What I claim is:

1. An incendiary projectile consisting of a shell having a plurality of bores therein, a plurality of smaller caliber projectiles in said bores, means within each small projectile for preventing its forward through-passage through an obstruction, and means for moving said means to the exterior of

the shell upon impact of the shell with the obstruction.

2. An incendiary projectile consisting of a shell having a plurality of bores therein, a smaller caliber projectile in each bore, normally inoperative means carried by each projectile for preventing its through-passage through an obstruction, and mechanism operable upon impact with the obstruction for rendering said means operative.

3. An incendiary projectile consisting of a shell having a plurality of bores therein adapted to receive a smaller caliber projectile, a plurality of smaller caliber projectiles in each of said bores, a slot in each projectile, means normally within each subcaliber projectile for preventing its through-passage through an obstruction, and mechanism operable upon impact with the obstruction for projecting said means through the slot in the projectile.

4. An incendiary projectile consisting in a shell having a plurality of holes in the surface thereof, an incendiary compound within said shell, a plurality of arms pivotally mounted in said shell and adapted to move from a position parallel to the axis to a position radial thereto, means for holding said means in a position parallel to the axis, and means extending forwardly of the shell for releasing said arms.

GEORGE L. PASS,
